PAGE 2

FIG. 1 is a front elevational view of a house showing my new design;

FIG. 2 is a rear elevational view;

FIG. 3 is an elevation thereof as seen from the right of FIG. 1; and

FIG. 4 is an elevation thereof as seen from the left of FIG. 1.

FIG. 5 is an enlarged fragmentary perspective view thereof as seen from the central portion of the house as shown in FIG. 2.

The conventional shingle on the roof and the brick on the walls which are only partially disclosed in the views on the drawing are understood to cover the entire surfaces shown.

I claim:

The ornamental design for a house, as shown and described.
